(57) **CLAIM**

The ornamental design for a storage box set, as shown and described.

DESCRIPTION

FIG. 1 is a front, right and top perspective view of a storage box set, showing my new design;

FIG. 2 is a rear, left and bottom perspective view of the storage box set of FIG. 1;

FIG. 3 is a front, right and top perspective view of the storage box set of FIG. 1, shown with one of the smaller storage boxes removed;

FIG. 4 is a front, right and top perspective view of the storage box set of FIG. 1, shown with one of the smaller storage boxes removed, where the removed smaller storage box is shown in another configuration;

FIG. 5 is a front view of the storage box set of FIG. 1, shown with one of the smaller storage boxes removed from view;

FIG. 6 is a rear view of the storage box set of FIG. 1;

FIG. 7 is a left side view of the storage box set of FIG. 1;

FIG. 8 is a right side view of the storage box set of FIG. 1;

FIG. 9 is a top plan view of the storage box set of FIG. 1, shown with one of the smaller storage boxes removed from view;

FIG. 10 is a bottom plan view of the storage box set of FIG. 1; and,

FIG. 11 is a front, right and top perspective view of the storage box set of FIG. 1 in a closed configuration.

The broken lines shown in the drawings illustrate portions of the storage box set that form no part of the claimed design.

1 Claim, 11 Drawing Sheets
